UNITED STATES PATENT OFFICE

EDWARD R. CASEY, OF BROCKTON, MASSACHUSETTS

DESIGN FOR A SHOE

Application filed December 17, 1932. Serial No. 46,479. Term of patent 3½ years.

To all whom it may concern:

Be it known that I, EDWARD R. CASEY, a citizen of the United States, residing at Brockton, county of Plymouth, and State of Massachusetts, have invented a new, original, and ornamental Design for a Shoe, of which the following is a specification, reference being had to the accompanying drawing, forming part thereof.

Referring to the drawing:

Fig. 1 is a front perspective view of a shoe showing my new design, and

Fig. 2 is a plan view of the same.

My present invention comprises a plurality of contrasting openwork cut-out figures, the main portion of the upper being a representation of one figure, with a relatively small area on the front of the vamp and at the side of the arch being of a contrasting figure.

I claim:

The ornamental design for a shoe, as shown and described.

In testimony whereof, I have signed my name to this specification.

EDWARD R. CASEY.
